UNITED STATES PATENT OFFICE.

ROBERT F. TROXLER, OF EVANSVILLE, INDIANA.

PHOTOGRAPHIC-FILM WASHER.

1,035,274.

Specification of Letters Patent. Patented Aug. 13, 1912.

Application filed July 22, 1910. Serial No. 573,240.

To all whom it may concern:

Be it known that I, ROBERT F. TROXLER, a citizen of the United States, residing at Evansville, in the county of Vanderburgh and State of Indiana, have invented a new and useful Improvement in Photographic-Film Washers, of which the following is a specification.

This invention relates to certain useful improvements in photographic film washers, the object being to provide a film washer which is exceedingly simple and cheap in construction, and one in which the fixing solution will be thoroughly washed from the film without any danger of injuring the film in any way by handling the same.

A further object of my invention is to provide a film washer in the form of a nozzle in which one end of a film is adapted to be secured in such a manner that water passing through the nozzle will be delivered upon both sides of the film in order to thoroughly wash the same.

Another object of my invention is to provide a film washer which can be used to dry the film after the same has been washed, the nozzle serving the purpose of preventing the film from curling when the same is suspended in an inverted position.

With these objects in view, the invention consists in the novel features of construction, combination and arrangement of parts, hereinafter fully described and pointed out in the claims.

In the drawing forming a part of this specification:—Figure 1 is a front elevation of my improved film washer showing the film in position to be washed. Fig. 2 is an end elevation. Fig. 3 is a transverse section. Fig. 4 is a detail view of a modified form.

In carrying out my improved invention, I employ a nozzle comprising a cylindrical body A provided with an enlargement B, having a nipple C to which is connected a piece of rubber hose E which is adapted to be connected to a spigot or any other suitable water supply, and when in use I preferably connect the same to a spigot of a bath tub, it of course being understood that

the same can be used in any way desired. 50 The body is provided with a longitudinal slot having flanged edges forming spaced clamping members G which are provided with openings registering with one another, and through which pins H are adapted to 55 pass for securing the end of the film I between the same, and it will be seen that by placing the nozzle in a suitable support such as a bracket, the film will be held in such a manner that when the water is turned on 60 it will pass through the nozzle and be distributed upon both sides of the film so as to remove the chemical therefrom.

After the film has been thoroughly washed the flexible tube is detached from the nozzle, and a clip attached to the lower end of the film which is supported by a suitable bracket, whereby the nozzle will act as a weight in order to hold the film when suspended, so as to prevent the same from 70 curling.

While I have shown a nozzle constructed to hold one film, it of course being understood that by enlarging the same or joining a number of nozzles together a washer can 75 be formed for washing any number of films desired at one time.

In the modification shown in Fig. 4, I provide a nozzle with a pivoted lever J carrying pins K which are adapted to pass 80 through the openings of the film clamp for securing the same, and it will be seen that by this construction it will be only necessary to throw the lever up and down in order to secure a film, or release the same. 85

From the foregoing description it will be seen that I have provided a film washer in the form of a nozzle having an outlet in which the film is adapted to be secured, and an inlet to which a water supply pipe is 90 connected for supplying the water for washing the film.

What I claim is:—

1. A photographic film washer comprising a nozzle having a supply pipe connected 95 thereto, said nozzle being provided with a slot having its edges provided with depending flanges adapted to receive a film, and

means for securing the film between said flanges.

2. A photographic film washer comprising a cylindrical body having a longitudinal slot provided with depending flanges having oppositely disposed openings, members extending through said openings for securing

a film between said flanges, an enlargement formed on said body having a nipple and a supply pipe connected to said nipple.

ROBERT F. TROXLER.
